UNITED STATES PATENT OFFICE.

CHARLES H. CHATFIELD, OF RIPON, WISCONSIN.

GLOVE.

SPECIFICATION forming part of Letters Patent No. 735,342, dated August 4, 1903.

Application filed October 20, 1902. Serial No. 127,985. (No model.)

To all whom it may concern:

Be it known that I, CHARLES H. CHATFIELD, a citizen of the United States, residing at Ripon, in the county of Fond du Lac and 5 State of Wisconsin, have invented a new and useful Glove, of which the following is a specification.

This invention relates to gloves.

The object of the invention is to present 10 a glove composed of a minimum number of parts and in which its elements are constructed and assembled with a view to greatest comfort in use and as providing the highest wear-resisting qualities.

15 With the above-stated and other objects in view, as will appear as the nature of the invention is better understood, the same consists in the novel construction and combination of parts of a glove, as will be hereinafter 20 fully described and claimed.

In the accompanying drawings, forming a part of this specification, and in which like characters of reference indicate corresponding parts, there are illustrated two forms of 25 embodiment of the invention, each capable of carrying the same into practical operation, it being understood that the elements therein exhibited may be varied or changed as to 30 shape, proportion, and exact manner of assemblage without departing from the spirit thereof.

In the drawings, Figure 1 is a view in plan 35 of a glove-blank. Fig. 2 is a similar view of the middle-finger fourchette. Fig. 3 is a similar view of the ring-finger fourchette. Fig. 4 is a similar view of the thumb-blank. Fig. 5 is a view in plan of the glove-blank, showing a slightly-modified form of thumb-opening. Fig. 6 is a view in plan of the 40 thumb-blank to be used in connection with the glove shown in Fig. 5. Fig. 7 is a view of a complete glove constructed in accordance with this invention and having the form of thumb-opening shown in Fig. 1. Fig. 8 is a view of a complete glove constructed in accordance 45 with this invention and having the form of a thumb-opening shown in Fig. 5.

The body of the glove may be made of any suitable material and is slitted at 1, 2, and 3 50 to separate the sections 4, 5, and 6 of the little, third, and second fingers, respectively, and to separate the forefinger-section 7. The

sections 4, 5, and 6 progressively increase in length, as is usual in structures of this character, to agree with the different lengths of 55 the fingers named. The forefinger-section 7 is double-curved at its top and terminates with one member 8 of an inverted-V-shaped slit, the other member 9 of which separates the other section 10 or the little finger from 60 the blank. The middle-finger fourchette 11 is provided at its lower end with two tongues 12 and 13, separated by a gap having a curved edge 14 and a straight edge 15. The third-finger fourchette 16 is provided at one side of 65 its lower end with a tongue 17, having a curved edge 18 extending from the lower end of the tongue on a curve with the opposite side of the fourchette. The thumb-opening 19 is approximately half-egg shaped and is provided at its upper portion with a quirk 20, formed by a slit 21, the quirk being downwardly curved. The thumb member 22 is double-curved on its upper end to provide the 70 terminal of the thumb when the parts are associated with oppositely-curved edges 23 and 24, terminating in points 25, and then cut on a curve 26 to constitute the bottom portion of the thumb member.

In assembling the middle-finger fourchette 80 with the blank or body the following procedure is observed: The edge A B is sewed to the edge L M N, the edge B C to G G X, the edge C D to U T, the edge A E to V W, and the edge D E to V U. In assembling the 85 third-finger fourchette with the blank or body the edge G X is sewed to P O N, the edge F H to X Y, and the edge G H to T Y. In assembling the thumb member of the glove with the blank or body the edge I K is sewed to 90 R S Q, the edge K K X to Q X R, the edge I K to J K X. The fourchettes and thumb member being thus assembled with the blank, the ends of the fingers and thumbs are sewed together by either a lap-seam or an in-seam, as 95 may be preferred. When the parts of the glove are thus assembled, the usual seam running down between the middle and third fingers is obviated and in lieu thereof there is a seam crossing either the middle or third finger. The thumb-seam is thrown off the center, so that the wear does not come directly on the seam, thereby preventing destruction 100 of the seam by coming in contact with objects

handled and also rendering the glove easier to wear. By the disposition of the seam across either the middle or third finger the glove is rendered more durable and fits the hand more smoothly, and, moreover, the seam is protected in the use of the glove.

In the form of embodiment of invention shown in Figs. 5 and 6 the main difference is in the manner of assembling the thumb member with the body or blank. In this latter arrangement the thumb-opening extends down through the body of the glove or mitten to the point where the band or gauntlet is stitched on and is assembled therewith in the following manner: The edge *a e* is stitched to *h i j*, the edge *c d* to *f k*, the edge *c l* to *g h*, and the edge *a b* to *b l*.

The advantages of a glove constructed in accordance with either of the procedures defined are that those parts subjected to the greatest wear are effectively reinforced and by the manner of constructing the glove the cost of production is reduced to a minimum.

It is understood that the particular forms of thumb members and the manner of their assemblage with the blank may be employed to advantage on mittens or on any kind of a glove.

Having thus described the invention, what I claim is—

A glove having the inner member of its second and third fingers formed by connecting-fourchettes, the fourchette of the second finger having two tongues at the base thereof and the fourchette for the third finger having a single tongue at one side thereof, the fourchettes being united with the body portion of the glove by attaching one tongue of the fourchette of the second finger to the base of the member forming the first finger of the glove, attaching the other tongue of the fourchette of the second finger to the fourchette for the third finger, and a member forming the back of the third finger, attaching the tongue of the fourchette of the third finger to the base of the member forming the little finger, and attaching the remaining portions of the bases of the fourchettes to the palm portion of the glove.

In testimony that I claim the foregoing as my own I have hereto affixed my signature in the presence of two witnesses.

CHARLES H. CHATFIELD.
